CHARLES J. PILLIOD, OF TOLEDO, OHIO, ASSIGNOR TO THE PILLIOD BROTHERS COMPANY, OF TOLEDO, OHIO, A CORPORATION OF OHIO.

REVERSING VALVE-GEAR.

1,243,760.

Specification of Letters Patent. Patented Oct. 23, 1917.

Application filed December 28, 1912. Serial No. 739,019.

To all whom it may concern:

Be it known that I, CHARLES J. PILLIOD, a citizen of the United States of America, residing at Toledo, in the county of Lucas 5 and State of Ohio, have invented certain new and useful Improvements in Reversing Valve-Gears, of which the following is a specification, reference being had therein to the accompanying drawings.

10. The invention relates to valve gears more particularly designed for use on locomotives, and it is the primary object of the invention to obtain a construction of reversing gear in which an equal valve travel upon 15 opposite sides of the center of movement is obtained in all positions of adjustment of the cut-off.

In the operation of valve gears employing angularly-moving connecting rods, the 20 simple harmonic movement produced by the crank or eccentric is more or less distorted, due to the angularity of the rod. This results in a greater movement on one side of the center than upon the other side, and 25 where a reversing gear is employed it has been heretofore impossible to fully correct the distortion. My improved construction is one in which the errors due to rod angularity are so corrected or minimized that for 30 all practical purposes the movement of the valve is equidistant from the center on opposite sides thereof in both forward and reverse and in all positions of adjustment of cut-off.

35. My improvement is applicable to various specific constructions of valve gears, but as shown, is applied to a locomotive valve gear employing what is known in the art as the Marshall reverse.

40. In the drawings:

Figure 1 is a side elevation.

Fig. 2 is a plan view of the gear on one side of the locomotive.

Fig. 3 is a diagram illustrating the principle of operation.

Fig. 4 is a diagrammatic view of a modification.

Fig. 5 is a vertical section of a detail.

The specific construction shown in Figs. 50 1 and 2 is of that type in which the movement of the valve is produced partly by a connection to the cross-head of the corresponding cylinder, and partly by a connection to the cross-head of the cylinder on the 55 opposite side of the locomotive. This is

equivalent to the operation of the valve from two cranks set at an angle of 90° apart and operating through angularly movable rods. In detail, A is the cross-head on one side of the locomotive, which is 60 connected by a link B with a lever C, which in turn is connected by a rod D to a lever E substantially parallel to the lever C and fulcrumed in a cross-head F, slideable in ways G and connected to the valve rod H. The 65 opposite end of the lever E is connected by a rod I to the rod O having one end connected to a rock-arm P upon a rock-shaft Q by means of a reverse gear of the Marshall type, which in the present instance comprises the bell-crank lever J connected with the rod I and having its actuating arm connected by a link K with a pair of links L on opposite sides thereof, which links in turn are pivotally connected to a pivoted 70 yoke M, adjustable through the rod N to different angular positions. The pivotal connection of the links K and L also forms a connection for the rod O. This rock-shaft extends across the locomotive frame and is 75 actuated by a lever on the opposite side of said frame corresponding to the lever C, and actuated in a similar manner from the cross-head of the engine on that side of the locomotive. The lever C is also connected to a 80 rock-shaft Q', which extends across parallel to the rock-shaft Q, and is connected by elements not shown similar to the parts D E F G H I J K L M N O and P, forming the 85 valve gear for the opposite engine. 90

With the construction as above described, the valve rod H is actuated by the lever E through the combined action of the rods D and I. The former imparts to the valve all necessary lap and lead movement, while the 95 latter, through adjustment of the rod N and yoke M, will impart a variably accelerating movement, determining the degree of opening of the valve. Thus when the rod N and yoke M is in the central position shown 100 in Fig. 1, no movement is imparted to the bell-crank J and rod I, for the reason that the links K and L have their axes or pivots substantially in alinement and consequently the movement imparted to the links L 105 through the medium of the rod O and rock-arm P will only result in swinging the link K without actuating the bell-crank. On the other hand, if the rod N is actuated to adjust the yoke M to either side of its central 110

positions, the axis of the pivotal connection between links L and yoke M is thrown out of alinement with the axis of the pivotal link K and bell-crank J, whereby a movement is imparted to the bell-crank, varying in accordance with the position of adjustment of the yoke. This movement is reversed when the yoke is adjusted upon the opposite side of the center and correspondingly varied according to the position of adjustment.

As has been previously stated, it is the primary object of the invention to obtain equal valve movement upon opposite sides of the center in all positions of adjustment of the yoke, and also equal movement when the yoke is adjusted to corresponding positions upon opposite sides of its neutral point. This has not been heretofore accomplished with the type of reversing gear such as above described, as irregularities are introduced by the angular movement of the rods, which give unequal movements both in respect to the opposite sides of the center of movement of the valve and also with respect to opposite sides of the reversing mechanism. I have overcome this defect by introducing a corrective in the mechanism intermediate the cross-head and the bell-crank lever J, the result being the correction or the minimizing of errors to a point where for all practical purposes the valve movement is uniform.

The principle of my improved construction is best illustrated in the diagram, Fig. 3. As therein shown, the arc described by the swinging of the rock-arm P on the rock-shaft Q has unequal segments in the movement produced by the first 90° and the second 90° of movement of the engine crank on opposite sides of its dead center. In the former, the segment is elongated by the straightening of the rod, and in the latter is proportionately shortened so that the position of the rock-arm P, when the engine crank is on dead center, is indicated at a Fig. 3, and the length of the arc from the initial point b is greater than the arc to the opposite end of movement c. To correct this inequality, the arm P, instead of being arranged parallel to the link K, is angularly offset as indicated, and this offset produces in the movement imparted to said link through the connecting rod O, a correction of any inequality existing between the arcs a b and the arcs a c. The movement is affected by the angularity of the rod O in different positions of adjustment of the yoke M, but by properly selecting the relative lengths of the radius arms and the positions of the centers of movement, an almost perfect correction is obtained. Thus in the diagram Fig. 3, the arc d e describes the path of movement of the swinging link L when the yoke M is adjusted to its extreme

position to the right of the center, indicated by the point f. Also the arc g h similarly represents the path of movement of said link when the yoke is adjusted to the extreme position to the left of the center, indicated at i. The arc j k is the extreme length of angular movement of the bell-crank J when actuated by the link K and the exact center of this arc is the point z. The arc P Q measures the angular movement of the other arm of the bell-crank J. As shown in Fig. 3 the lines representing the bell-crank J are positioned between the yoke M and the rock-arm P, the equal valve movement being fully as well illustrated as if the bell-crank were represented in the position as shown in Figs. 1, 2 and 4.

It will be observed by inspecting this Fig. 3 that a series of points m m', etc., set off in the arc b c, corresponding to equal angular movements of the actuating engine crank, are irregular or unequal in the two portions of said arc a b and a c. It will also be seen that the arcs n n', etc., described by the angular movement of the rod O from each of the points m m', etc., will intersect the arcs d e and g h, and that the series of points produced by such intersections will be substantially regular on opposite side of the intersecting point o of said arcs d e and g h. Furthermore, the point of intersection in the arcs d o and h o are respectively equidistant from the same point in the arc j k, and in like manner the points in the arcs e o and g o are respectively equidistant from the same point in said arc j k. This will produce an equal angular movement of the bell-crank J with a given movement of the rock-arm P whether the yoke M is adjusted to the point f or to the point i, so that in reversing the gear the valve movement will be equal but opposite. This is also true for every point of intermediate adjustment of the yoke M upon opposite sides of its center. Again the angular movement imparted to the bell-crank J by the travel of the link K to successive points along the arc d o is equal to the movement of said link along the arc e o to the corresponding point therein; which means that the movement is equal and corresponding upon opposite sides of the center of movement of the bell-crank.

The correction of distortion due to angularity having been effected in the movement of the bell-crank J, it is obvious that this movement can be imparted without further distortion to the valve rod through the medium of the rod I and lever E. Briefly reviewing the entire movement from the engine crank-shaft to the valve, it will be seen that the simple harmonic movement of the crank is first distorted through the angular movement of the connecting rod upon the opposite side of the locomotive. This distorted movement is transmitted through the

link B and lever C to the rock-shaft Q and to the rock-arm P upon the opposite end thereof. Correction of the distortion is then effected by the angular offsetting of the rock-arm P, and the proportion and relative arrangement of elements between the same and the bell-crank J. The corrected movement is transmitted from the bell-crank through the rod I to the lever E and from the latter through the cross-head F and rod H to the valve.

My improvement is also applicable to the type of valve gear in which the valve is actuated solely from the engine on one side 15 of the locomotive which it controls. This, as shown in Fig. 4, includes a crank S attached to the crank pin T of the locomotive and having a pin U which is arranged at an angle of 90° about the crank from the 20 pin T. This pin U is connected by a rod V with an extension W of the rock-arm P, and actuates the latter in the same manner as where actuated by the crank on the opposite side of the locomotive. The same 25 distortions due to the angularity of the rod V are introduced in the movement of the rock-arm P, but these are corrected by the mechanism as previously described.

What I claim as my invention is:

30 1. The combination with a reciprocating piston engine having a rotary part, of a valve gear including a rock arm and means including a connecting rod and cross-head for imparting angular motion from the rotary 35 part to said rock arm, an engine valve, means connecting said rock arm with the engine valve including a reverse gear of the Marshall type, said rock arm being at such an angle to the neutral axis of the reverse 40 gear when said piston is on dead center that the effect on the valve of angular distortions in the motion of the rock arm is eliminated.

2. In a valve gear for a reciprocating piston engine having a valve, a rock arm, an

actuating mechanism therefor introducing 45 angular distortions in the motion thereof, and means connecting said rock arm with the engine valve including a reverse gear of the Marshall type, said rock arm having its longitudinal axis arranged non-parallel 50 to the neutral axis of said reverse gear when said piston is on dead center.

3. In a valve gear, the combination with a reciprocating actuating member having its movement distorted from a simple harmonic 55 movement, of a reciprocating valve and means intermediate said reciprocating actuating member and reciprocating valve for transmitting an equal movement to the latter on opposite sides of the center reversible 60 in direction and variable in amplitude, said means including a rock arm receiving motion from said actuating member, a reversing gear of the Marshall-type and a connection between said rock-arm and reversing 65 gear, the longitudinal axis of said rock arm and the longitudinal axis of the reversing gear in neutral position being non-parallel when the engine is on dead center.

4. In a valve gear, the combination with an 70 actuating mechanism for an engine valve, introducing angular distortions and a rock arm, of a pivoted yoke, a bell-crank lever, links pivotally connecting said yoke and bell-crank lever, and a rod connecting said 75 rock arm and links, the longitudinal axis of said rock arm and one of said links diverging when the yoke is in neutral position and the engine is on dead center whereby the angular distortions are corrected and the 80 valve movement is uniform on opposite sides of the center.

In testimony whereof I affix my signature in presence of two witnesses.

CHARLES J. PILLIOD.
